UNITED STATES PATENT OFFICE

HARRY J. MOYER, OF PHILADELPHIA, PENNSYLVANIA.

JIGGER FOR SEPARATING COAL AND SLATE.

1,225,157.

Specification of Letters Patent.

Patented May 8, 1917.

Application filed July 14, 1915. Serial No. 39,916.

To all whom it may concern:

Be it known that I, HARRY J. MOYER, a citizen of the United States, residing at 1516 Wingohocking street, Philadelphia, in the county of Philadelphia and State of Pennsylvania, have invented a certain new and useful Jigger for Separating Coal and Slate, of which the following is a specification.

The purpose of my invention is to provide a jigger tank having a water-pulsating plunger therein with a box bottom section movable upwardly and downwardly in response to varying weights of content, with or without corresponding movement of the box or the remainder of the bottom, and to damp movement of the bottom upwardly to prevent the plunger from forcing the bottom or box upwardly with the content, interfering with the separation, and to damp the movement of the bottom downwardly to support the box content.

A further purpose of my invention is to damp the movement of an upwardly and downwardly movable jigger box bottom or box subjected to plunger action without objectionable lost motion in the damping connections.

A further purpose of my invention is to provide bodily vertical movement for a jigger bottom, with or without the rest of the box, subject to plunger water action, automatically adjust the height of the bottom or box by the proportion of slate to coal therein and determining the slate feed from the box by the height of the box.

A further purpose of my invention is to operate a vertically movable jigger box at differing heights inversely proportional to the quantity of slate in the box while maintaining a slant for the screen bottom of the box which shall advantageously feed the slate toward the outlet, varying the slant at different heights, where desired, to improve the control over the movement of the slate.

Further purposes of my invention are to maintain substantially the same slope of the screen bottom of a jigger box while the bottom with or without the box is automatically moved in a vertical direction corresponding in position to the proportion of slate to coal in the box; to counterbalance the weight of a jigger box or box bottom by weighted levers whose effective fulcrum distances change to balance the box in different positions, according to the weight of the content; to provide means for maintaining a

movable jigger box in raised position when first operated, as after cleaning, in order to provide it with an initial bed for operation; to provide positive automatic closing means for an outlet door for slate in a movable jigger box; and to make the bottom of the box or a section of the bottom movable instead of the entire box where an existing jigger is being altered or where, for any other reason provision for movement of the entire box proves unduly expensive or otherwise inexpedient.

Further purposes of my invention will appear in the specification and in the claims thereof.

I have preferred to illustrate my invention by several forms thereof which are practical, efficient and inexpensive and which at the same time well illustrate the principles of my invention.

Figure 1 is a broken vertical section through a jigger embodying the preferred form of my invention.

Fig. 2 is a transverse section of the structure shown in Fig. 1, omitting the conveyors and showing some additional matter.

Fig. 3 is a detailed section of the outlet door and counterweight.

Fig. 4 is a broken elevation of a modified form of box-supporting lever.

Fig. 5 is a broken view, partly in section, showing a second modification of the box support.

Fig. 6 is a broken elevation showing the use of supports for different parts of my jigger box adapted to tilt the box as it rises and falls.

Fig. 7 is a broken vertical section through a modification.

Fig. 8 is a broken front elevation of the structure seen in Fig. 7, omitting the elevators.

Fig. 9 is a broken detail section at right angles to Fig. 7.

In the drawings similar numerals of reference indicate like parts.

The coal and slate in a mixed state enter the jigger box and by means of a baffle plate are directed to the bottom of the jigger box and the well-known exaggerated difference in weight between coal and slate when immersed in water causes the coal to work to the top and the slate to remain on the bottom when the mass is agitated by water being forced upward through the perforated bottom of the jigger box by plunger action,

While there has been no difficulty in obtaining a continuous and nearly uniform feed of coal over the top edge of the jigger box which can be economically handled by a conveyor, the withdrawal of the slate has been irregular and unsatisfactory.

In the best collieries or preparation plants it has been the practice for the operator to watch the jigger and tap the slate at intervals. Frequently, through his inattention or errors of judgment, the slate has been allowed to accumulate until some of it passes over with the coal, injuring its quality and risking its condemnation. Rejigging involves the labor of the second handling and breaks some of the coal, reducing its value.

breaks some of the coal, reducing its value.

At other times the slate is tapped for too long a time until coal is wasted by passing out with the slate. Even when the slate is properly withdrawn by this method the intermittent character of the feed of slate prevents economical conveyer handling and does not allow the jigger to be worked at its maximum capacity.

25 Various efforts have been made to improve this condition by attempting automatic continuous withdrawal of the slate. Most of these efforts have proposed counterweighted doors to be opened by the slate when it has
30 accumulated to sufficient depth for the weight of the slate to overcome the counter-weighting. This has been unsuccessful for various reasons, one of which is the absence of a counterpoise which varies as the weight
35 on the door or gate changes its position. Another is the absence of a damper or stabilizer to prevent jiggling of the door by the agitated coal and slate.

Another system has proposed to hinge the jigger box along one edge and allow the increasing weight of the content due to increasing proportion of slate to swing the grate bottom downwardly until the slate can be discharged. This is open to serious objection due to the cut-off character of outlet closure used and to the fact that the slope of the grate bottom, if proper for discharge, is so much reduced with a lower slate bed as to lose the desirable feeding of the slate toward the outlet. The absence of a damper or stabilizer to prevent jiggling of the jig box bottom as well as the coal and slate is a serious defect here also. So far as I am aware, no stabilizer capable of preventing the jiggling of a movable jig box or box bottom or section of the box or bottom has ever been used in a jigger.

My invention is directed primarily to utilization of part of or the entire weight of the box content as the basis for control of the outlet, and stabilizing the box against rapid movement in either direction. I apply it with a type of slate gate which eliminates the danger of the slate sticking in the opening. My invention is made effective by

moving the box or part of the bottom of the box bodily by means of the weight of the content or of counterbalancing weights to a height corresponding with the weight of the content and damping the box or part of the bottom thereof against jiggling or movement by reason of the operation of the plunger or other agitating means.

I purpose directing this application to counterbalancing of a box bottom screen, whether the box be rigidly attached thereto or movably connected therewith and whether it be the entire bottom or only a section thereof; and the stabilizing of this counterbalanced box bottom screen against sudden movement in either direction. In a copending application, Serial No. 46,607, filed August 21, 1915, for movable bottom screen jigger, I claim the species having the structure applied to a bottom screen which screen is movable with respect to the box. 80 85 75

Describing my preferred form in detail:—
The tank 1 contains the water in which the jigger box is to be immersed. This reaches some such level as 2, above the reciprocable plunger 3. As is usual, this plunger operates at one side of the jigger box or in the rear thereof, in a space provided by a baffle or wall 4, so that the effect of the plunger action shall be directed upon the perforated bottom 5, of the coal- and slate-receiving box 6, rather than upon the sides of the box

At the front of the tank I provide casings or boots 7 and 8 in proximity to the outlets for coal and slate respectively, within which casings any suitable conveyers 9 and 10 are located for the purpose of continuously carrying away the coal 11 and slate 12. The combined coal and slate is delivered to the box through a chute from any suitable pocket, such as 13, or other storage or supply source.

As is generally the case with jiggers in which the water agitation is provided by a plunger, the mixed coal and slate is delivered to the jigger box back of a baffle, such as 14, which is spaced from the bottom of the box by a distance which is adjustable through the sliding closure 15, rod 16 and adjusting mechanism shown at 17. 115

The coal passes out from the box at the top over the mouth 18, at which point the front is lowered for this purpose. The slate progresses toward the front because of the slope of the perforated bottom of the box and passes out through a front opening at 19. The slate is protected close to the opening against crowding from the material directly above it by means of a baffle 20. 115 120

I prefer to pivot the door 21 above the opening and have it close toward the outwardly moving slate in order to avoid choking of the slate between the door and frame. The counter-weighted arm 22 tends to open this door permitting free discharge of the 130

slate whenever the position of the box is low enough. The lifting of the box causes automatic closing of the door by engagement of any part of the door, such as flange 23, with a relatively fixed member 24, which may be a part of the surrounding frame.

In this form I provide movement of the entire box, rather than of the bottom or a portion of the bottom only, the first named being the preferred form where new jiggers are being constructed. The box is guided so as to permit vertical movement of the box and contents, including the baffle 14 by any suitable means of which I have shown one form, best seen in Fig. 2. In this form the box is provided with brackets 25 to which rods 26 are secured. When slight tilting of the box during its movement is desired, as with the construction seen in Fig. 6, the connection may be made by pins 27, allowing slight front and back movement of the upper parts of the rods due to the effect of this construction (Fig. 6) in raising and lowering one part more rapidly than the other. Brackets 28 within the tank form stops limiting the downward movement of the box.

Brackets 29 upon the box engage brackets 30 within the tank to check upward movement of the box.

Where the tank is to move at the same rate at all points, brackets 29 are secured to the rods and brackets 30 perform a guiding function also.

At the upper ends of the rods 26, they are connected by a top 31, in order to conveniently utilize a single damping or stabilizing mechanism for regulating the upward movement of all of the rods instead of requiring separate stabilizing means for each rod or counterpoise.

The top is connected with the rods by a hinge connection comprising ears 32 and 33 connected by a pin 34, and this same pin is conveniently engaged by the slotted or forked end 35 of a lever 36 for each rod 26. The levers are shown as having fixed fulcrum points 37 in my preferred form and as provided with counterweights, preferably two to each lever, illustrated at 38 and 39, which may be adjusted for any run of coal and slate being handled and are secured in position by set screws 40, 41.

It will be evident that the effective distances between the counter-weights and the fulcrum points varies with the angular positions of the levers, according to the harmonic law, while the effective distances from the fulcrums to the pins 34 is substantially the same in all positions of the levers.

I prefer to use arcs of movement of the levers 36 so that the levers shall be horizontal or a little below the horizontal in the lowermost intended position of the box.

Within this range, differing weights of the

box and contents, due to varying percentages of coal and slate will cause the box to balance reliably at varying heights, the effective balancing power of the weights being reduced as the box rises, because the proportion between the lengths of the two arms on opposite sides of the fulcrum 37 varies, as stated.

The amount of movement required to reach a new position of equilibrium for any given change in weight will be greater toward the bottom of range of movement than toward the top. This is also desirable as it will more quickly check any sudden or unusual outward flow of the slate, which otherwise might occur to disturb the desirable uniformity of increase of depth of slate toward the front.

In order that the pulsations of the plunger 3 may be confined effectively to the perforated bottom of the box and the interior of the box, it is desirable to reduce water leakage around the sides of the box, as much as possible, without interfering with free upward and downward, preferably strictly vertical movement of the box. This has been done by flanges 42 at the sides of the box, flange 43 at the front and flange 44 at the rear. The flanges 42 are connected at the back with vertical flanges 45 substantially in line with the rear wall of the box closing off the space at the side of the box from free water entry at the rear.

The flanges 42, 44 and 45 lie close enough to the walls of the tank to prevent appreciable fluctuation of water between them and the flange 43 cooperates with a tank flange 46 for the same purpose. At the lowermost position of the jigger box passage of water between the flange 42 and the tank walls is additionally protected by flanges 47 against which the flanges 42 engage.

Each stroke of the plunger gives an impulse to the box and its contents of coal and slate. If the box be balanced and free to move it will respond to the pulsations caused by the plunger, reducing or destroying the effect of these pulsations upon the coal and slate to lift and scatter them so that they will separate according to their subsiding values with the slate on the bottom. My damper or stabilizer is intended to take the thrust of these successive water impulses caused by the plunger, holding the box so that the full impulse will be effective for separation of the contents, without interfering with the slower movements of the box to reach a point of equilibrium for each changing weight and equally effective in its stabilizing function in all positions of the box.

As will be pointed out later, the principle is equally effective in stabilizing a movable bottom or section of a box bottom, or other box part and constitutes a very important

part of my invention as applied to a bodily movable box or any movable part thereof intended to be operated by the weight or pressure of the box content and desirably held in 5 partially moved position to permit continuous, as distinguished from intermittent feed of slate.

While obviously the means of effectively damping vertical movement of the jigger box 10 to prevent it from being jiggled by reason of the plunger impulses may be greatly varied in view of my disclosure to stabilize by other means or apply it in a single stabilizer or in distributed stabilizers to other parts 15 of the movable mechanism, just as various other guiding and supporting means would be effective, I have illustrated a dash pot stabilizer filled with oil or other suitable liquid for this purpose, as representing the most 20 effective form and have applied it to the entire box through the rods as the most convenient mode of application.

The stabilizer is operatively connected with the table 31 by means of rod 48 and pin 25 49 upon which it may be free both to rock and to move (if desirable to have the front and back of the box rise and fall at different rates) without introducing lost motion.

The stabilizer comprises a cylinder 50, 30 filled with oil, or other suitable liquid, and piston 51 with which the rod is connected. The cylinder is mounted upon any frame 52, here shown as connected with the walls of the tank and leakage of oil from the bottom of 35 the cylinder is prevented by gland 53.

I prefer to allow leakage of oil through the piston, as by opening 54, rather than around it, in the operation of the dash pot and protect against lost motion due to air in 40 the oil by putting the oil under pressure. I have shown one means of doing this by means of a pipe 55 which may be filled to any desired height to produce the required pressure. I have also shown an outlet pipe 56. 45 The pipes are controlled by valves 57. The damper or stabilizer cylinder can be made large enough so that the movement of the piston will be as slow as desired owing to the small amount of oil or other liquid which 50 will pass around the piston and through the opening 53.

Upon any suitable support, such as bracket 58, I pivot a lever 59 connected through yoke 60, slot 61 and pin 62, with the rod 48, 55 so that pressure at the opposite end of the lever 59 will tend to lift the box 6 and lifting of the lever will tend to lower the box.

Because of the presence of pieces of metal in the mixed coal and slate, as delivered, 60 which metal lies in the bottom of the box and does not feed out freely with the slate, as well as for other reasons, it is desirable to clean out the box from time to time. This may be accomplished by lifting the end 63 of 65 the lever 59 and holding it up by placing the

pin 64 through the opening 65 and under the lever, resulting in a continued flow of content out through the opening 19 until the box is emptied sufficiently to clean out the bottom grating at least. Inlet of coal and slate is 70 preferably stopped during this time. At the start, the lever end 63 can be lifted very easily, but as the box empties, the unbalanced counterpoise weight would become excessive and the pin 64 is supplied to take this 75 pressure.

When the box is again supplied with mixed coal and slate, it will lack the slate bed initially and it is desirable to form this bed quickly. This may be readily accomplished 80 by the operator standing upon the end of the lever 59, as at 66, holding the box up to its uppermost position for a time to prevent flow through the bottom opening until the slate has had a chance to accumulate on the 85 bottom in sufficient quantity to operate automatically.

In order to show that the counterpoise means, even if of lever form, as preferred by me, can be varied in different ways from that 90 shown in my preferred form while still obtaining the difference in proportion of lever arms by which balancing of the box at different heights for different weights is so conveniently obtained, I have illustrated 95 other forms in Figs. 4 and 5.

Fig. 4 shows a reversal of that shown in Fig. 2, in that the end of the lever 36' is pivoted about the pin 34 while the fulcrum point is made adjustable by slotting the lever, 100 as at 67, where the pin 37 passes through it.

In the form shown in Fig. 5, the lever 36' is pivoted at its end in the pin 34 and the fulcrum point is fixed relatively to the length 105 of the lever.

The pin 68 at the fulcrum point is connected with the pin corresponding in position to pin 37, by means of a link 69. The variation in effective leverages is obtained by making the weight 39' freely movable 110 along the length of the lever 36' under the control of a cam slot guide 70, in a bracket 71. A pin or pins upon the weight travel in this slot to move the weight along the lever according to any predetermined law, 115 as the lever rises and lowers.

In Fig. 6 I show two constructions corresponding generally to the counterpoise levers of Fig. 2, but differing in that the lever 36 at the left is pivoted, as at 34, closer to 120 the pin 37, than is the case with the lever 36'. If one of these types of lever be used for the set supporting the front of the vertically movable box and the other for the set supporting the rear thereof, it will be 125 evident that either the front or rear as preferred will rise and lower more rapidly than the other part of the box, slightly canting the box during its movement vertically. If the front be moved the more rapidly, for 130

example, a greater slope may be given the bottom of the box in its lowermost position for the purpose of more rapidly feeding out the slate when the percentage of slate is running high and the lowermost position of the box has been reached than when the percentage of slate is running low or when the box is not feeding slate at all, but accumulating a slate bottom. This results without interfering with a considerable range of box movement during which the slope of the bottom of the box is maintained, though it be not uniform.

In some uses of my invention it will not be desirable to make the entire jigger box movable. This is particularly true of reconstruction of existing jiggers where the owners do not care to make as much change as would be required for this. In such cases a part of the benefit of my invention may be obtained by making the bottom of the jigger or a part of the bottom of the jigger movable in the box and I have illustrated one form of the latter construction in Figs. 7, 8 and 9. From my two disclosures, application of my stabilizer, variable weight counterpoise, movable bottom, with or without movement of the box, etc., generally to the art will readily be perceived by those skilled in it.

In this second form of my invention I illustrate the same general character of jigger but omit the guiding construction for the box. The greater part of the perforated bottom is fixed and it may be longitudinally stiffened, as in the case of my first form, by a strip 72, (Fig. 2) if desired. A portion of the bottom at the front, as 73, is made movable and, as with the box, when it is movable, I prefer to have it lift and lower bodily rather than merely swing, for example. It is guided in this movement by a transverse flange 74 upon the adjoining edge of the fixed portion of the bottom and by the inner face of the tank at the front, as at 75.

The flange 76 secured to the under side of the movable section of the bottom at the front edge assists in the guiding function and prevents accidental intrusion of slate within the slate outlet opening 19' in the tank beneath the movable section. In the illustration the movable section is connected with the stabilizer piston rod 48' by a plurality of rods 77 and a frame 78 connecting them. The rods are shown as three in number, two located near the edges and the third passing through the longitudinal stiffening strip 72'. These afford full support for the weight upon the movable section and to brace it against tilting. It is kept from moving toward the front and rear by the flanges and endwise by the walls of the tank.

I show the same general form of variable

counterpoise for the weight of the bottom section as for the weight of the box in my other form, but connect the levers 36 with the two end rods 77 within the free spaces at the sides of the box, showing them as extending in planes at right angles to the planes of the levers in the other form. I require but two levers and support the outboard end of the pin 34' from the frame by a bracket. The pin 37' is supported in 75 a boss 79 upon the bracket 80.

The door is controlled positively in both directions of movement by rods 81 which are attached at one end to the lever 36 and at the other end to an arm 82 upon the extended door pivots 83. The frame 52 is cut away at 84 to permit adjustment of the height of the closure 15.

The lever 59 of my preferred form may be applied or omitted as desired. Where a section of the bottom only is movable the weight upon it is so much less than that of the entire box and contents that it is not so necessary. The position of the section may easily be within the range of control 90 of the operator by lifting or lowering the levers 36.

I prefer to lift the opening in the tank at its upper edge slightly above the uppermost position of the movable bottom, in 95 order that the range of movement of the bottom need not be great in order to provide sufficient outlet for the slate. This does not allow leakage of the slate, even where the bed of slate may be thin and the bottom in its uppermost position, because of the door and is particularly desirable where a section only of the entire bottom is to be moved. It avoids the cut-off objection to the closure.

In operation, the mixed coal and slate are fed to the jigger box and the box or section is raised (either by lever 59 or by the levers 36) until the slate has settled to the bottom definitely enough to form a bed. 100 The box or bottom is then allowed to reach its own level in proportion to the weight and operative jiggling is begun.

The upward movement of the box in my preferred form will be too gradual to be interfered with by the feed of coal and slate into the box, and I have not throttled this feed by any adjustable gate for this reason. The movement of the coal from the chute into the box will be sufficient to permit the 110 box to rise without backing up any coal into the chute.

When the slate accumulates in the bottom sufficiently to move the box or bottom downwardly and open the slate outlet this 125 movement takes place gradually both because of the counterpoise used and, more especially, because of the stabilizer. Without the stabilizer a sudden feed of slate when the outlet is opened would result in 130

the corresponding rise of the box or section shutting off the feed until there was another accumulation; and this has proved to be one of the causes of failure in what might be 5 called the counter-weighted-trap-door type of jiggers to which reference has previously been made. Their failure has been the more complete because their counterweights have not balanced at different heights for different 10 weights and the trap has moved the full distance open when the required accumulation has been reached, resulting in a relatively sudden feed of slate, reducing the weight to below that of the counterweight 15 and resulting in a sudden closure. The spasmodic movements of slate have also tended to disturb the distribution of slate and coal, allowing coal to pour down toward the point of discharge to take the place 20 of the slate discharged instead of having the slate steadily progress from the rear to the front, maintaining a substantially uniform upper surface as high as is expedient in the jigger. The coal which tends to 25 crowd down toward the point of discharge interferes with the normal progress of the slate toward the front and must be displaced before the slate can fill this space up to again exert the required pressure upon the 30 trap.

In my jigger no sudden feed of slate would occur because the door is opened gradually, but quickened flow of slate will not result in closing the door, because of the 35 stabilizer, but will only start a slow upward movement of the box or bottom which will be corrected soon by the natural and uniform movement of the slate from the rear to the front.

40 Where the front and rear of the box or bottom are moved at different rates of speed as, for example, by using variant leverages for their respective support, as in Fig. 6, the feed of the slate may be accelerated 45 either in the upper or lower range of movement of the box or bottom, as preferred. Ordinarily it would be desirable to accelerate in the lower positions of the box or bottom, so as to provide for more rapid 50 movement of the slate when the bed of slate was deepest.

By varying the counter-weights for any particular percentage of slate being handled, the box or bottom may be safely maintained at nearly its maximum rate of slate 55 discharge.

The uniformity of slate feed secured by me greatly increases the capacity of a jigger of any given size, since the feed of the 60 jigger must be restricted at present to avoid undue accumulation of slate and with my invention the feed can be adjusted to maintain a height of slate equal nearly to the allowable maximum, as at present operated, thus providing a greatly increased slate

output and a corresponding increase in the amount of coal which can be handled.

It will be evident that the screen bottom affords the ultimate support for the coal and slate and that the bottom, as well as sections of it, may be considered to be movable when this movement actually takes place, even though it be because of the movement of the entire box and not separate therefrom and I have therefore considered the movable bottom as including both my structures shown, in one of which the entire bottom moves along with the box and in the other of which a bottom screen, though not comprising the entire bottom screen, moves independently of the box.

It will be evident that my jigger is simple in construction, requires a minimum of water, avoids loss of fine materials and breakage of the coal and requires much less 85 attention than jiggers of other forms.

It will be evident that the various features of my invention are independently desirable and also coöperate to produce a concrete unitary result which has not previously 90 been attained.

It is further evident that differences may be made in the guiding, supporting, counter-weighting and stabilizing structures used, as well as in the forced movement of the box, without departing from the spirit and scope of my invention, as protected in the claims hereof and without interfering in the effective combination of the structures performing these functions, or any of them to secure additional results by reason of their combination.

Having thus described my invention, what I claim as new and desire to secure by Letters Patent is:—

1. In a device of the character stated, a water tank, a jigger box adapted to extend within the water, having slate and coal outlets and including an upwardly and downwardly movable screen bottom varying the extent of slate outlet, reciprocable means for producing relative movement between the water and the screen bottom, a stabilizer for the movable bottom and counterbalancing support for the movable bottom.

2. In a device of the character stated, a water tank, a jigger box having a slate outlet and providing an upwardly and downwardly movable screen bottom support for mixed slate and coal, affecting the extent 120 of slate outlet, reciprocable means for producing relative movement between the water and the screen bottom, dash pot means directly connected with the bottom to resist the upward thrust of the water due to the 125 plunger action and counterpoise means for supporting the weight of the slate and coal.

3. In a device of the character stated, a water tank, a jigger box having a slate outlet adapted to receive slate and coal to be 130

separated and providing a vertically movable support for the same which affects the size of the outlet, reciprocable means for producing relative movement between the 5 water and the support, dash-pot retarding mechanism directly connected to the movable support, and counter-balancing means engaging the connection varying in counterbalancing effect with the height of the 10 support.

4. In a device of the character stated, a water tank, a plunger reciprocable therein, a vertically movable screen bottom supporting mixed slate and coal, means for counterbalancing the weight of the slate and coal, a dash pot and connections to damp vertical movement of the screen bottom, liquid in the dash pot and a connection extending above the dash pot to receive liquid and 20 bring pressure upon the liquid in the dash pot.

5. In a device of the character stated, a water tank, a plunger reciprocable therein, an upwardly and downwardly movable bottom support for mixed slate and coal and counter-weighted lever means for supporting the slate and coal and having the proportion of length of lever to the support and counter-weight respectively upon opposite sides of the fulcrum point automatically varied with changing heights of support.

6. In a device of the character stated, a water tank, a plunger reciprocable therein, an upwardly and downwardly movable bottom support for mixed slate and coal, counter-weighted lever means for supporting the slate and coal, having a variable proportionate leverage upon opposite sides of the lever pivot point and a stabilizer for damping the up and down movement.

7. In a device of the character stated, a tank adapted to hold water, a reciprocable plunger therefor, a jigger box vertically movable in its entirety adapted to feed from the bottom of the box at its lower positions and compensating counterweighted levers and connections having variant lengths of lever holding the box at variant heights according to the combined weight of coal and slate therein.

8. In a device of the character stated, a jigger tank adapted to hold water, a plunger reciprocable therein, a coal- and slate-receiving box vertically movable within the water and having an outlet for coal at the top and for slate at the bottom in its lowered position and dash pot means for damping the movement of the box.

60 9. In a device of the character stated, a casing adapted to receive water, a plunger reciprocable therein, a box adapted to receive coal and slate and having a slate outlet at the bottom, guides providing for upward and downward movement of the box and at-

tendant-operated means for maintaining the box in raised position while forming a bottom of slate for the content of the box.

10. In a device of the character stated, a tank adapted to receive water, a plunger 70 reciprocable therein, a vertically movable box adapted to receive coal and slate and having a slate outlet, guides for the box and counter-weighted levers for supporting the box, the length of lever from the box support to the fulcrum having a different proportion to that from the fulcrum to the counter-weight at different heights of the box to vary the output through the outlet.

11. In a device of the character stated, a 80 tank adapted to hold water, a plunger reciprocable therein, a vertically movable box adapted to receive coal and slate, having a slate outlet and variant-fulcrum counter-weighted lever support, having different proportions from the counter-weight to the fulcrum and fulcrum to the box respectively for different ends of the box to raise and lower the box at different rates.

12. In a device of the character stated, a 90 tank adapted to hold water, a plunger reciprocable therein, a vertically movable box having a slate discharge opening adapted to receive coal and slate, guiding means for providing the vertical movement, counter-weighted supports for the box and dash pot means for stabilizing of the box.

13. In a device of the character stated, a tank adapted to hold water, a plunger reciprocable therein, a vertically movable box 100 having an opening along one lower edge, counter-weighted means having a variable fulcrum for balancing the box at different heights in proportion to its weight, a door for the outlet opening and automatic means 105 engaging the door to close it to variant extents, in proportion to the height at which the box is balanced.

14. In a device of the character stated, a tank adapted to receive water, a plunger reciprocable therein, a box adapted to receive coal and slate, cooperating guide members directing the movement of the box, levers connected with the box having variant relations of the fulcrum to the point of box support and counter-weight and a dash pot stabilizer connected with the box to reduce movement thereof responsive to the water pulsations caused by the plunger.

15. In a device of the character stated, a 110 water tank, a jigger box therein, having a slate outlet, a reciprocable plunger for giving impulse to the water, a box bottom movable up and down by reason of variant weight of overlying box content and tending 115 to close and open the outlet, a damper directly connected with the movable bottom reducing movement of the bottom responsive to the plunger action, variant fulcrum lever counter-weighting for the movable 120 130

bottom supporting differing weights at different heights, a door for the slate outlet and connections between the door and the movable parts for opening the door as the bottom lowers.

16. In a device of the character stated, a water tank, a reciprocable water impact plunger therein, a jigger box adapted to extend into the water, having a slate outlet, 10 an upwardly and downwardly movable bottom in proximity to the outlet, counter-weighting means for supporting the movable bottom, a dash pot and direct connections between the dash pot piston and movable 15 bottom, retarding movement of the bottom in both directions.

17. In a device of the character stated, a water tank, a reciprocable plunger therefor, a jigger box extending into the water and 20 having a slate outlet, a movable box bottom in proximity to the slate outlet, a dash pot having a piston therein, rigid connections between the dash pot piston and the movable bottom supporting the bottom against tilting, 25 guiding means supporting the bottom laterally and counter-weighting for the movable bottom.

18. In a device of the character stated, a water tank, a reciprocable plunger therefor, a jigger box extending into the water and 30 having a slate outlet, a movable box bottom in proximity to the slate outlet adapted to tend to open and close it, a dash pot having a piston therein, rigid connections between the dash pot piston and the movable bottom, 35 counter-weighting for the movable bottom and a door for the outlet operated by reason of the movement of the bottom.

19. In a device of the character stated, a water tank, a reciprocable plunger therefor, 40 a jigger box extending into the water and having a slate outlet, a movable box bottom in proximity to the slate outlet adapted to move transversely of the opening, leaving it partially open in its uppermost position, 45 counter-weighted means for varying the height of the bottom in inverse proportion to the weight of the content upon it and a door preventing outlet of slate when the bottom is in its uppermost position.
